CLAIM

The ornamental design for a water conditioning system, as shown and described.

DESCRIPTION

FIG. 1 is top-down perspective view of a water conditioning system in accordance with a first embodiment, showing our new design;

FIG. 2 is a bottom-up perspective view of the embodiment shown in FIG. 1;

FIG. 3 is a front elevation view of the embodiment shown in FIG. 1;

FIG. 4 is a rear elevation view of the embodiment shown in FIG. 1;

FIG. 5 is a left-side elevation view of the embodiment shown in FIG. 1;

FIG. 6 is a right-side elevation view of the embodiment shown in FIG. 1;

FIG. 7 is top-down plan view of the embodiment shown in FIG. 1; and,

FIG. 8 is a bottom-up plan view of the embodiment shown in FIG. 1.

The broken lines in FIGS. 1-16 represent the bounds of the claimed design and form no part thereof.

1 Claim, 8 Drawing Sheets
